[57] CLAIM

The ornamental design for a shoe stitching, as shown and described.

DESCRIPTION

FIG. 1 is a perspective view of shoe stitching showing my new design;
FIG. 2 is a right side elevational view;
FIG. 3 is a left side elevational view;
FIG. 4 is a front elevational view;
FIG. 5 is a rear elevational view; and,
FIG. 6 is a top plan view.
The broken line showing a shoe in FIGS. 1-6 is for illustrative purposes only and forms no part of the claimed design.

FIG. 1

FIG. 2

FIG. 3

FIG. 6

FIG. 4

FIG. 5
